FLOOR RADIOUNIT

Edward F. Andrews, Evanston, Ill., assignor to
 Andrews-Hammond Corporation, Chicago, Ill.,
 a Corporation of Illinois

Application March 20, 1928. Serial No. 263,007

21 Claims. (Cl. 250—14)

My invention relates to a radio receiving set and particularly to a portable set wherein the entire receiving mechanism is mounted in a single readily movable housing. The principal object 5 of this invention is to provide a structure for a complete radio receiver, totally different from current practice, which may include a loud speaker, which shall be readily portable about the room or house, which will stand directly on 10 the floor, and which will at the same time locate the controlling and indicating mechanism at a height convenient to the hand of a sitting, standing or reclining operator. A further object is to provide a set as above described which can be 15 housed in a relatively small compact metal container which will be cheap to build and at the same time will lend itself to a pleasing decorative effect from all sides. A further object is to provide a set of this character which may be connected to any light socket by a plug on the end 20 of a relatively long flexible cable, which cable and plug may constitute the only connections necessary to operate the set, antenna and ground 25 connections as well as power for the set being derived, if desired, from this single connection to the lighting circuit. A further object is to provide such a set which shall have its center 30 of gravity located very close to the floor upon which it stands, so that it will have a minimum tendency to tip over if pushed or kicked.

Other objects will appear from time to time in the course of the specification and claims.

I illustrate my invention more or less diagrammatically in the accompanying drawings, where- 35 in—

Figure 1 is a side elevation of my device;

Figure 2 is a vertical cross-section on an enlarged scale; and

Figure 3 is a partial wiring diagram.

Like parts are indicated by like symbols throughout the specification and claims.

Referring first to Figures 1 and 2, A indicates any suitable base or ground engaging member. Upwardly projecting therefrom are a plurality 45 of vertical supports or columns A¹, arranged adjacent the edge of the base member A. Secured to the upper ends thereof is an upwardly and inwardly inclined or reduced housing member A² which may be provided with a plurality 50 of apertures A³ and which terminates in an inwardly reduced portion A⁴.

Secured to the portion A⁴ in any suitable manner is the lower edge B¹ of the hollow control column B. The column B is expanded at its 55 upper end as at B² to form a supplemental hous-

ing for the control and indicating members here- 60 after described. B³ is any suitable handle mem- ber, preferably secured to the housing B². Located on the base A are the heavier elements 65 of the set, especially the power supply devices such as the transformer C, the choke coils C¹ and the filter condensers C². In the particular construction disclosed in Figure 2 the audio fre- 70 quency transformers C³ C⁴ are also located on the base A and the gang of tuning condensers D also 75 rests upon the base and projects upwardly there- from.

Positioned upon the supports or columns A¹ intermediate their ends is any suitable interme- 75 diate support, herein shown as an annular shelf E, upon which are mounted the vacuum tubes 80 generally indicated as E¹ and the radio frequency transformers enclosed in shields and diagram- matically illustrated as E². The rectifier tube E³ is mounted on a small shelf or support E⁴, 85 because it is of greater height than the other tubes.

Immediately above the tubes E¹ and the radio frequency transformers E² is positioned a loud 90 speaker, herein shown as including a motor G and a vibrating cone G¹ supported upon the connecting rod G². The cone G¹ is shown with a hole G³ through which passes a shaft D¹ which connects the condenser gang D with the control 95 and indicating mechanism positioned within the housing B². It will be understood that any suitable dial mechanism may be employed.

For rotating the shaft D¹ and the rotor plates 90 of the condenser gang secured thereupon, I indicate a rotatable knob D⁵ extending above the housing D², which may be employed to rotate the dial located inside or upon the housing B², connected directly to the shaft D¹ and carrying upon it graduations for the purpose of indicating the frequency which the set is tuned to 95 receive. A suitable volume control mechanism and a switch for turning on and off the power supply in the set is also conveniently located in or upon the housing D², being herein shown as 100 D⁶ D⁷ respectively.

In order to permit access to the interior of the device, I provide a vertically movable housing member, herein shown as a cylinder H the bottom of which normally rests upon the base A when 105 it is in position, the top of which in such case engages the lower edge of the housing member A². When access is desired the member H may be raised. It will be understood of course that I do not wish to limit myself solely to this specific 110

means of having access to the interior of the housing, but I find it a practical arrangement.

Referring to Figure 1 J indicates a flexible conductive cable which will be understood as having two conductors which extend from the two point plug J¹ to the base member A, whence any suitable conductive connections are made with the various parts of the set.

I illustrate a partial wiring diagram in Figure 3 which is thought to be sufficient to illustrate the characteristic features of the circuit. J² J³ are the separate conductors of the cord J. J⁴ is a switch adapted to be located on the control compartment B² for actuation by the manual control member D⁷. J⁵ is the primary coil of the power transformer shown as C in Figure 2. A multiplicity of secondary windings J⁶ serve the purposes indicated in Figure 3, the wiring connections therefor not being shown in detail. When the switch J⁴ is opened the current is completely turned off to all parts of the set. J⁷ is a radio frequency amplification stage of which J⁸ is the inductance. J⁹ is a resistance across the inductances J⁸, variable for purpose of volume control. This may be operated by the volume control knob D⁶ mounted upon the housing D² earlier described and shown in Figures 1 and 2. J¹⁰ is an alternating current tube supplied by one of the secondary windings J⁶. The plate J¹¹ is connected to the succeeding radio frequency stage of the set. J¹² is a condenser connected between the grid side of the inductance J⁸ and the primary of the transformer J⁵. This connection allows the electric lighting circuit to function as the antenna or radio frequency connector for the radio set. It will be realized that this arrangement is merely one of several specific arrangements that can be employed.

The cylindrical construction of the container H provides an advantageous set structure, being compact, cheap to make and easily and cheaply made a decorative article of furniture. It permits the convenient location of the tubes around the periphery where they are easily accessible when the cylindrical casing H is removed. This shape also conforms to the shape of a cone type of loud speaker, with its cone lying in a horizontal plane.

It is advantageous for many reasons to locate the power devices at the bottom, first, because they are the heaviest and to so locate them lowers the center of gravity of the set, giving it stability; second, because they are more rugged and would be less apt to be damaged if kicked or pushed with the foot; and third, because it is not necessary to provide particularly ready access to them. The tubes and radio frequency portions of the set can be advantageously located above the power units, as there is greater need of accessibility to the tubes and the radio frequency structure is generally lighter. The gang condenser D extends down into the lower compartment.

It is thought advantageous to use a horizontally located cone type of loud speaker as this can be incorporated with only a small increase in the over-all dimensions. If the cone is situated above the tubes with its apex up it utilizes the space in the tapered portion of the housing A² which taper is very desirable from the point of view of appearance.

Also, the location of the speaker at the top of the device makes it possible for the sound to pass through the apertures A³ with a minimum of interference from the other parts of the set. This

construction produces a relatively low compact small unit with its heaviest portions located adjacent the floor. It is economical to build and can be enclosed completely in a decorative metal housing which is itself quite small and light.

If a radio set is to be carried about from place to place and set down in a position adjacent to the chair or couch occupied by the operator, it is desirable that it be adapted to be set upon the floor as otherwise the presence of a table or some suitable object upon which it can be set is required. However if the device is made small and compact, as is dictated by economy in production and ready portability, it will be too low to have its indicating and controlling mechanism located upon one of its sides as is the present practice. Therefore to bring the indicating and controlling mechanism to within easy reach of the operator and to provide a handle by which the set can be transported readily from one place to another, the column B is provided, projecting upwardly from the set, and carrying at its upper end the handle B³ and the indicating control container B² located at a height which makes operation from a sitting, standing or reclining position easy and convenient. It will of course be apparent that sets of different dimensions will require columns of varying lengths to bring their controls to the proper height, a very convenient height being twenty-two inches.

For this type of set to present its maximum advantages it should be made as small and light as possible consistent with rugged construction and economy in production. Large and heavy sets are much less adapted to this arrangement, it being generally preferable to divide the set into two parts in such cases, as described in my co-pending application No. 263,005, filed March 20, 1923. Upon removal of the plug J¹ from any socket, the set may be picked up by the handle B³, and can be easily transported to any desired location in the house, where the mere insertion of the plug J¹ into a light socket immediately renders it ready for operation.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

In particular it will be understood that where in the claims I describe the container as located adjacent the floor I wish this term to be taken as sufficiently broad to include devices wherein the container actually engages the floor and those where it is positioned somewhat above the floor as for example upon supporting feet or base.

I claim:

1. A portable radio receiving apparatus which includes a container located adjacent the floor, tuning means positioned in said container, control means for operating said tuning means, positioned above said container, located at a level convenient for the hand of a standing, seated or reclining operator and actuating connecting means between said control means and said tuning means, and a housing extension projecting upwardly from said container and about said connecting means, and of substantially less cross-sectional area than said container, an enlargement at the upper end of said extension, an indicating dial within said enlargement, a con-

- nection between said dial and said connecting means and means for rotating the dial.
2. A portable radio receiving apparatus which includes a container located adjacent the floor, 5 tuning means positioned in said container, control means for operating said tuning means positioned above said container at a level convenient for the hand of a standing, seated or reclining operator, an actuating connection between said 10 control means and said tuning means, a housing extension projecting upwardly from said container and about said connecting means and of substantially less cross-sectional area than said container, an enlargement at the upper end of 15 said extension, and an indicating dial within said enlargement adapted to be actuated in unison with said tuning means. 80
3. A portable radio receiving apparatus which includes a container located adjacent the floor, 20 an extension of said container of substantially reduced cross-sectional area projecting upwardly from said container, tuning means in said container, control and indicating means located at the upper end of said extension, and an actuating connection between said control means and said tuning means extending through said extension. 85
4. A portable radio receiving apparatus comprising a container adapted to be located adjacent the floor, a radio receiving set housed within said container, a loud speaker of the cone type located in the upper portion of said container with its axis vertical, a housing of reduced diameter projecting upwardly from said container, control and indicating means mounted at the upper end of said housing, and an actuating connection extending therefrom through said housing into said radio set. 90
5. A portable radio receiving apparatus comprising a container adapted to be located adjacent the floor, a radio receiving set housed within said container, a loud speaker of the cone type located in the upper portion of said container with its axis vertical, a housing of reduced diameter projecting upwardly from said container, control and indicating means mounted at the upper end of said housing, and an actuating connection extending therefrom through said housing and through said loud speaker into said radio set. 100
6. A portable radio receiving apparatus comprising a container adapted to be located adjacent the floor, said container having a substantially frusto-conical upper end, a radio receiving set housed within said container, a loud speaker of the cone type located within said container above said set with its axis vertical and its apex pointed upwardly so that it conforms to the frusto-conical upper end of the container, a housing of reduced diameter extending upwardly from the upper end of the frusto-conical end wall, control and indicating means supported at the upper end of said housing, and an actuating connection extending therefrom through said housing into said radio receiving set. 110
7. A portable radio receiving apparatus comprising a container adapted to be located adjacent the floor, said container having a substantially frusto-conical upper end, a radio receiving set housed within said container, a loud speaker of the cone type located within said container above said set with its axis vertical and its apex pointed upwardly so that it conforms to the frusto-conical upper end of the container, a housing of reduced diameter extending upwardly 115
8. A portable radio receiving apparatus comprising a container adapted to stand on the floor, a radio set in the lower part of said container, a speaker of the cone type located within said container and above said set with the axis of the cone vertical, the periphery of the cone approximating an outline to the surrounding wall of the container, controls located above said set and above said speaker, and actuating means connecting said controls to said radio set, said actuating means extending through the speaker. 120
9. A radio receiving set comprising a speaker having a conical diaphragm located with its axis vertical, a base located below said speaker and located at right angles to said axis, a plurality of tubes mounted in a circle on said base adjacent the edge thereof, and a housing having a substantially cylindrical wall enclosing said tubes and surrounding the marginal edge of said diaphragm. 125
10. A radio receiving set comprising a cone type speaker, a base located adjacent said speaker in spaced relation thereto, said base being substantially coaxial with the cone of said speaker and a plurality of tubes and radio amplifying devices mounted on said base and arranged in a ring in substantial alignment with the periphery of the said cone. 130
11. A radio receiving set comprising a cone type speaker, a base located in alignment with said speaker and substantially at right angles to the axis thereof, a plurality of tubes and radio amplifying devices mounted on said base and arranged in a ring in alignment with the edge of said speaker, and a surrounding enclosure protecting said tubes and devices and readily removable for replacement and adjustment of said tubes and devices. 135
12. A radio receiving set comprising a speaker having a conical diaphragm, a circular base in alignment with said diaphragm and located at right angles to the axis thereof, a plurality of tubes and radio amplifying devices mounted on said base adjacent the edge thereof, and a substantially cylindrical housing enclosing said tubes and amplifying devices and surrounding the marginal edge of said diaphragm. 140
13. A radio receiving set comprising a cone type speaker with its axis vertical, a base located below said speaker, a plurality of radio devices mounted on said base and arranged in a line below the perimeter of said speaker cone, a column extending upwardly above said speaker, and controls mounted on said column. 145
14. A radio receiving set comprising a cone type speaker, a base located below said speaker and at right angles to the axis thereof, a plurality of tubes mounted on said base and arranged around its edge, a surrounding enclosure protecting said tubes and readily removable for replacement and adjustment of said tubes, a column extending above said speaker, and radio controls mounted on said column. 150
15. A radio receiving set comprising a cone type speaker, a base located below said speaker at right angles to the axis thereof, a plurality of radio tubes mounted on said base and arranged in a line below the perimeter of the speaker cone, 155

a column extending upwardly above said speaker, and radio controls mounted on said column.

16. A radio receiving set comprising a cone type speaker, a base located below said speaker and at right angles to the axis thereof, a plurality of radio devices mounted on said base and arranged along its edge, a surrounding enclosure protecting said devices and readily removable for replacement and adjustment of said devices, a column extending upwardly above said speaker, and radio controls mounted in said column.

17. A radio receiver having a substantially circular base, a cone type loud speaker mounted substantially in the center of said base with the axis of the speaker cone substantially perpendicular to said base, and thermionic tubes mounted in a circular series around the outer portion of said base between the base and the periphery of said speaker cone.

18. A radio receiver comprising a loud speaker of the cone type, radio devices located behind the speaker cone, controls located in front of said cone, and operating means connecting said controls to said devices extending through said cone.

19. A radio receiver comprising a loud speaker of the cone type, radio devices located behind the speaker cone; controls located in front of said cone, and operating means connecting said controls to said devices extending through said cone, said cone being provided with openings permitting said operating means to pass freely therethrough out of contact with the cone.

20. A radio receiver comprising a loud speaker of the cone type, radio devices located behind the speaker cone, a supporting wall in front of said speaker cone, control means mounted on said wall, and operating means connecting said controls to said devices extending through said cone, said cone being provided with openings permitting said operating means to pass freely therethrough out of contact with the cone.

21. In a radio receiver, in combination, a cone type speaker, radio devices behind the speaker, controls in front of said speaker, and operating connections between said controls and devices extending through said speaker.

EDWARD F. ANDREWS.
